BILGE PUMP

Albert R. Pierce, Jr., South Dartmouth, Mass.

Application October 18, 1945, Serial No. 623,141

5 Claims. (CL. 103—59)

1

This invention relates to a pump for removing water from the bilge of small boats.

In the use of small boats of a size which are left in the water but which have an open cockpit, water accumulates in the boat bilge by reason of rain or possibly from leakage through the hull. It is necessary to pump out these boats with a hand pump or a bailing can prior to use. This practice takes time and in some cases where heavy rains occur for an extended period, the boats are liable to get so low in the water that they will fill and capsize.

One of the objects of this invention is to provide an arrangement so that a boat of the above character will be kept practically dry at all times.

Another object of this invention is to provide a continuously driven pump which may operate indefinitely and should any water occur in the boat the same will be immediately removed.

Another object of this invention is to provide a pump which may be driven by the wind which usually is present at some part of the day, especially at the time of rain fall, which will cause a sufficient pumping action to remove any water which may have accumulated in the boat during any period of inaction of the pump because of lack of wind.

Another object of this invention is to provide an easily driven pump by balancing gravitational load which may occur therein so that the same may be easily driven by the wind with a small propeller.

Another object of this invention is to provide a pump which is sufficiently simple so that it is not liable to get out of order.

Another object of this invention is to provide a reciprocating head which will be guided in a casing which surrounds it.

With these and other objects in view, the invention consists of certain novel features of construction, as will be more fully described and particularly pointed out in the appended claims.

In the accompanying drawings:

Fig. 1 is a sectional view through a small boat illustrating my pump as positioned therein.

Fig. 2 is a sectional view through the pump.

Figure 3 is a section on a somewhat larger scale illustrating the casing at the upper end of the pump showing the reciprocating head therein.

Fig. 4 is a sectional view in exploded relation of the plunger of the pump.

Fig. 5 is a sectional view in exploded relation of the valve at the lower end of the pump and a portion of the body.

2

Fig. 6 is a sectional view on line 6—6 of Fig. 5.

Fig. 7 is a fragmental sectional view illustrating the valve of the plunger in assembled relation and both assembled in the tubular body part of the pump.

In proceeding with this invention, I provide a tubular body of usual piping which will be of a length sufficient to lift the column of water to the desired height for gravity discharge therefrom. 10 This tubular body may vary in length for different usages to which it may be placed. A valve is provided at the lower end and a motor arrangement at the upper end for reciprocating a piston in the body for pumping water above the piston to such a height that it may run by gravity from a conduit leading from the body. I spring load the piston and operating parts so that their gravitational force or weight plus the weight of the column of water which is provided up to the 15 outlet will be balanced and the power which is necessary will be small so that it may be supplied by the wind. A wind responsive propeller is provided on a shaft at the upper end which will be easily driven by the force of the wind. This 20 rotating action is translated into a reciprocating movement by an eccentric.

With reference to the drawings, 10 designates the hull of a small boat having a combing 11 about an open cockpit 12. Water is shown at 30 13 which has accumulated in the bilge of the boat. The boat is provided with a center board box 14 which houses a center board to be lowered for use in sailing the boat. The pump which is shown installed in this boat is designated generally 15 and is mounted by means of brackets 16 and 17 fastened to the center board box. These brackets are so arranged as to enable a tubular body 18 to be inserted in these brackets to support the same vertically as illustrated in 35 Fig. 1.

This tubular body 18 may be made of various constructions but is suitably formed from a brass pipe of the required length. The brass pipe is fitted at its lower end with a valve 19 which has a tubular part 20 extending into the lower 40 end of the pipe where it is held by a set screw 21. This tubular part 20 is turned down from the larger piece of stock forming a shoulder 22 which engages with the end of the pipe. A bore 23 receives the ball valve 24 which engages the valve seat 25 at its lower end to control the smaller opening 26 which extends axially through the lower part of the valve. Cross-conduits 27 and 50 28 communicate with the vertical opening 26 and are of a size to so control the entrance into 55

the pump that particles which will not pass through the pump will be excluded. An abutment pin 29 limits the movement of the ball valve 24 upwardly.

The piston which is designated generally 30 as shown in Fig. 4 comprises a body 31 having bores of several different sizes extending axially therethrough. The upper bore 32 is threaded for engagement with the rod to which it is attached. Another bore 33 just below this bore 32 is somewhat larger and is connected therewith by a taper 34 while the lower bore 35 is of a still larger size to receive the valve seat member 36 which has a valve seat 37 so that the ball valve 38 may seat thereon to cause the piston to lift water which is above this valve 38 in the piston when the piston moves upwardly. Water may pass the valve on the downward stroke of the piston and pass out through the openings 39 in the piston. A recess 40 on the outer surface of the piston receives a piston ring or some soft packing 41 so as to provide a tight sliding fit for the piston along the inner surface of the tubular body.

At the upper end of the tubular body a casing 42 is provided which is usually cast in the form of a hollow body 43 closed by a cover plate 44 providing a hollow interior 45 for receiving the working parts. A boss 46 is provided on the back wall of the casing through which a bearing opening extends. An oilless bushing 47 is provided in this opening. Closure plate 44 is also provided with a boss 48 which has in it an oilless bushing 49. Both of these together provide spaced bearings for a shaft 50 which is rotatably mounted in this casing. A handle 51 is provided on one end of the shaft while a propeller hub 52 is provided on the other end of the shaft which has propeller blades 53 extending from the hub and of a shape so that when placed in the wind the propeller will rotate and cause the shaft 50 to rotate. An eccentric 54 is provided on the shaft 50 to rotate therewith. A head 55 shown in Fig. 3 has an opening 56 to receive the eccentric 54 and is provided with a tongue 57 to extend through an opening 58 in the upper wall of the casing so as to be guided in its reciprocating movement. A member 59 is guided in the lower part 60 of the casing and this member is connected by means of a screw 61 having a slotted head to the eccentric so that both ends of the eccentric are vertically guided in the casing. This lower part 60 of the casing extends downwardly to provide a collar 62 which fits the upper end of the body 18 so as to provide a good long bearing connection therewith. Connecting rod 63 is threaded at its opposite ends and one end is screwed into the piston 30. Thus, as the eccentric moves, the head 55 of the piston will also be moved reciprocatingly in the body 18.

An outlet 64 is provided at the proper level to conduct water from the body 18. The height of this outlet will be such in the showing at Fig. 1 as to discharge the water into the center board box, where it is conducted overboard or out of the boat.

In order to balance gravitational force of the reciprocated parts as well as the weight of the water in the body, I provide a spring 65 which acts between one end of member 59 and the abutment plug 66 which is secured in the tubular body 18 by prick punch impressions 67 which force portions of the body inwardly to engage this member 66. Tension on this spring may be varied by the different location of the member 66 in the body or it may be varied by pulling out the coils of the spring so that greater tension is provided. The spring is adjusted to exert force in accordance with the weight of the parts and column of water as above the piston and approximately balances these. This spring loading enables the pump to operate very easily, thus requiring very little wind force for rotation of the shaft which in turn causes reciprocating movement of the piston.

I claim:

1. A portable bilge pump comprising a tubular body of uniform diameter from its lower end upwardly throughout its length to its head, said lower end being adapted to be placed in the bilge of a boat, a piston reciprocably guided in said body having a valve therein, a casing at the upper end of the body having a rotatably mounted shaft at right angles to the axis of the body, a wind actuated propeller for rotating said shaft, an eccentric rotatable with said shaft, a head guided in said casing and reciprocated by said eccentric, and a rod connecting said head to said piston, a discharge opening from said body, a long spring surrounding and loading the rod and parts moving therewith to counterbalance the same in an amount to include the weight of the column of water in the body up to said discharge opening.

2. A bilge pump as set forth in claim 1 wherein said head has a tongue extending through the casing to be guided by the edges of the opening through which it extends.

3. A bilge pump as set forth in claim 1 wherein a member for connecting said head to said rod is guided in said casing.

4. A bilge pump as set forth in claim 1 wherein said head is guided in its straight line movement by guides on opposite sides of said eccentric.

5. A bilge pump as set forth in claim 1 wherein said head is guided in its straight line movement by guides on opposite sides of said eccentric and the end of said guide is connected to said rod.
